UNITED STATES PATENT OFFICE.

WILLIAM HENRY HANNAN, OF SYRACUSE, NEW YORK, ASSIGNOR TO
WILLIAM HERBERT HANNAN, OF SAME PLACE.

THILL-COUPING.

SPECIFICATION forming part of Letters Patent No. 487,005, dated November 29, 1892.
Application filed April 27, 1892. Serial No. 430,882. (No model.)

To all whom it may concern:

Be it known that I, WILLIAM HENRY HANNAN, a citizen of the United States, residing at Syracuse, in the county of Onondaga and State of New York, have invented a new and useful Improvement in Thill-Couplings, of which the following is a specification.

This invention relates to a thill-coupling which is provided with a clamping device, whereby the thills can be readily attached to or detached from the vehicle.

The object of my invention is to improve the construction of the coupling and to render it reliable and efficient in operation.

15 In the accompanying drawings, consisting of two sheets, Figure 1 is a side elevation, partly in section, of a thill-coupling having an open draft-eye and provided with my improved clamping device, the parts being shown in a coupled position. Fig. 2 is a longitudinal section thereof showing the parts in an uncoupled position. Figs. 3 and 4 are vertical transverse sections in lines $x-x$ and $y-y$, Fig. 1. Fig. 5 is a side elevation, partly in section, of a thill-coupling having a divided draft-eye attached to the axle and provided with my improvements. Fig. 6 is a vertical transverse section in line $z-z$, Fig. 5. Fig. 7 is a side elevation, partly in section, of a thill-coupling having a divided draft-eye attached to the thill-iron and provided with my improvements. Fig. 8 is a horizontal section in line $v-v$, Fig. 7.

Like letters of reference refer to like parts in the several figures.

In the construction represented in Figs. 1, 2, 3, and 4, A represents the front axle, and B the thill-clip, secured to the axle and provided with a tie-bar b. The front end of the tie-bar is provided with a rigid draft C, which has the form of a semicircular hook and is provided with a socket d in its upper side.

E represents the thill-iron, provided at its rear end with a knuckle or wrist e, which is seated in the socket d when the parts are in their coupled position.

F represents a clamping-lever, whereby the knuckle of the thill-iron is firmly drawn against the draft-eye. This clamping-lever is arranged lengthwise underneath the draft-eye and is pivoted with its front end by a pin

g to a lug g', formed on the under side of a carrying-plate H, arranged lengthwise between the draft-eye and the clamping-lever. The carrying-plate is pivoted at its rear end 55 by a pin h to a depending lug h', formed on the rear portion of the draft-eye. The upper side of the carrying-plate is provided with a socket i, in which is arranged a block or filling i', of rubber or other elastic material, which 60 bears against the under side of the draft-eye.

J represents a link or loop, whereby the knuckle of the thill-iron is connected with the clamping-lever. This link consists of two upright bars j, j, arranged on opposite sides of 65 the draft-eye and horizontal cross-bars J' J², connecting their upper and lower ends. The upper cross-bar J' passes horizontally through the center of the knuckle, while the lower cross-bar J² is arranged in a transverse groove 70 or notch k, formed in the clamping-lever outside of the fulcrum of the latter. The notch or groove k is sufficiently open to permit the link to be detached from the lever.

k' represents a stop formed on the under 75 side of the carrying-plate and which limits the rearward movement of the clamping-lever.

When it is desired to couple the thills to the vehicle, the clamping-lever is swung forwardly, as represented in Fig. 2. The knuckle 80 of the thill-iron is then placed in the socket of the draft-eye and the lower cross-bar of link is placed into the groove k in the clamping-lever. The clamping-lever is then swung rearwardly on its fulcrum until the lever rests 85 against the stop on the under side of the carrying-plate, whereby the knuckle is firmly drawn against the draft-eye and the rubber block is compressed. In this position of the parts the point at which the link is attached 90 to the clamping-lever lies in rear of the fulcrum of the lever and the tension of the rubber block holds the lever locked against the stop, as represented in Fig. 1, and exerts a constant downward pressure against the link and automatically takes up any wear of the parts.

When the rubber block becomes worn, it can be easily removed from the carrying-plate and replaced by a new one. The carrying-plate is provided in rear of its pivot with a toe k², which 100 strikes against the under side of the draft-eye when the parts are in an uncoupled po-

sition, as represented in Fig. 2, thereby limiting the downward movement of the carrying-plate and clamping-lever and preventing the rubber block from becoming detached.

5 In Fig. 5 and 6 my improvements are shown applied to a thill-coupling, in which the draft-eye is composed of a lower rigid section L and an upper movable section L', hinged with its front end to the front end of the rigid section and provided at its rear end with a lip l. In this construction the connecting link or loop is permanently attached with its lower end to the clamping-lever and detachably connected with its upper end to the lip of the movable draft-eye section. The carrying-plate is pivoted at its front end and connected with the clamping-lever near its rear end.

If desired, my improvements may be applied to a thill-coupling in which the thill-iron is provided with a rigid eye-section m and a movable eye-section m', both sections embracing a coupling-bolt or wrist n, secured in ears n' formed on the clip B, as represented in Figs. 7 and 8.

25 I claim as my invention—

1. The combination, with the draft-eye and the knuckle or wrist seated in said eye, of a movable carrying-plate provided with an elastic block or filling bearing against said eye, a clamping-lever pivoted upon said plate, and a link connecting the clamping-lever with the part to which the pressure is applied, substantially as set forth.

2. The combination, with the draft-eye and the knuckle or wrist seated in said eye, of a carrying-plate pivoted to said eye and provided with an elastic block or filling bearing against said eye, a clamping-lever pivoted upon the plate, and a link connecting the clamping-lever with the part to which the pressure is applied, substantially as set forth.

3. The combination, with the draft-eye and the knuckle or wrist seated in said eye, of a carrying-plate pivoted to the eye and provided with a socket, an elastic block or filling

seated in said socket and bearing against the eye, a clamping-lever pivoted upon the carrying-plate, and a link connecting the clamping-lever with the part to which the pressure is applied, substantially as set forth. 50

4. The combination, with the draft-eye and the knuckle or wrist seated in the eye, of a carrying-plate pivoted to the eye and having a toe on one side of its pivot which is adapted to bear against the eye and provided with an elastic block or filling which bears against the eye, a clamping-lever pivoted to said plate, and a link connecting the clamping-lever with the part to which the pressure is applied, substantially as set forth. 55

5. The combination, with the draft-eye and the knuckle or wrist, of a carrying-plate pivoted to the eye and having a projecting stop on its under side and an elastic block or filling on its upper side, a clamping-lever pivoted to said plate and striking said stop when the clamping-lever is tightened, and a link connecting the clamping-lever with the part to which the pressure is applied, substantially as set forth. 60

6. The combination, with the open draft-eye provided with a depending lug and the knuckle or wrist seated in said eye, of a carrying-plate pivoted to said lug and provided with a socket in front of its pivot, an elastic block or filling seated in said socket and bearing against said eye, a toe formed on the carrying-plate in rear of its pivot and adapted to bear against the eye, a clamping-lever pivoted to the front portion of said plate, a link connecting the clamping-lever with the knuckle, and a stop formed on the carrying-plate, whereby the tightening movement of the clamping-lever is limited, substantially as set forth. 70

Witness my hand this 9th day of April, 1892.

WILLIAM HENRY HANNAN.
